UNITED STATES PATENT OFFICE

TRANQUILLO ZERBI, OF TURIN, ITALY, ASSIGNOR TO FIAT SOCIETÀ ANONIMA, OF TURIN, ITALY

CARBURETOR OF AIRCRAFT ENGINES FOR INSURING THE REGULAR ENGINE WORKING IN INVERTED LOAD CONDITIONS

Application filed May 23, 1930, Serial No. 456,470, and in Italy November 29, 1929.

It is known that the carburetors now in use for aircraft engines insure a regular fuel supply to the engine even with strong inclinations of the flying machine but wholly cease 5 from feeding the engine when the load is inverted. This condition is attained in two cases, viz. in continuous inverted flight and in sudden descents as under the action of air-holes.

10 This invention concerns a carburetor which insures the regular running of the engine to which it is applied in the above mentioned cases and the means for insuring this working is automatic and requires no operation by 15 the pilot.

In order to insure a regular feed in the carburetor according to this invention and in the two opposed conditions, the fuel inlet conduit instead of opening directly into the constant 20 level chamber extends into a distributing chamber from which two separate conduits are branched, which open into the constant level chamber. Of these two conduits one is 25 alternatively left in connection with said chamber and its outlet is adjusted by means of a suitable float level adjusting device, while the other conduit is closed by a device mounted in the distributing chamber. This latter device as well as the level regulator act automatically 30 on one or the other opening of the two conduits mentioned above according to the position taken by the flying machine.

A further object of this invention is to arrange the normal spray nozzles of the carburetor in proximity to the chamber bottom and to arrange one or more auxiliary nozzles in proximity to the chamber top, these auxiliary nozzles coming into action only when the load is inverted and a set of nozzles being always 40 at rest when the other set is working.

The accompanying drawing shows by way of example some constructional forms of the object of this invention.

Figure 1 is a longitudinal section of the carburetor.

Figures 2 and 3 are sectional views showing two further slightly modified constructions of the carburetor.

Referring to Figure 1, the carburetor comprises an annular chamber 1, in proximity to

the bottom whereof extend two ordinary spray nozzles 2 and 3, respectively, for the minimum speed and for normal speed, which communicate with a channel 7 opening to the outside through an air intake 8 in order to 55 brake and mix the fuel flowing through said spray nozzles.

In the suction pipe 4 of the carburetor is arranged a throttle valve 6 and a large Venturi tube 5 within which is lodged a second 60 Venturi tube 5a provided with holes, to which the mixture flows from the large spray nozzles through a conduit 3a. The fuel flowing from the small spray nozzle 2 is conveyed through a conduit 2a and the holes 4a formed 65 in the suction pipe 4 into proximity to the throttle valve 6.

In proximity to the top of the chamber 1 an auxiliary spray nozzle —a— is arranged which normally communicates with an air 70 intake conduit —b— opening to the outside in proximity to the bottom of the chamber. This spray nozzle —a— opens through the conduit 3a into the inner Venturi tube 5a 75 of the carburetor.

The chamber 1 carries a float 9 fast with a lever 11 articulated to a pivot 10 and provided with a needle 12 with conical ends. Two conduits 13 and 14 open opposite the conical needle ends into the space 1a formed 80 in the chamber 1 and extend to a distributing chamber 15. The fuel from the carburetor flows through a tube 16a into said chamber and is filtered through a wire-gauze 16b.

In the distributing chamber a slide 17 is 85 mounted on a guide 18 projecting into the chamber 15 and is provided with conical ends for closing one or the other opening of the conduits 13 or 14 according as it sinks in one or the other direction under the action 90 of its weight.

Atmospheric pressure is maintained inside the chamber 1 in the two opposed positions by a communication with the atmosphere established by the conduit —b— in normal flight and by the conduit 7 in inverted flight so as to prevent the flow of the fuel to the outside when the flying machine is turned upside down.

The carburetor according to this invention 100

works as follows: When the flying machine flies in normal position, corresponding to the carburetor shown in Fig. 1, the slide 17 keeps the conduit 14 closed and the fuel flows into the chamber 1 through the conduit 13. The fuel level is kept constant in the chamber 1 through the float 9 and needle 12 fast therewith which adjusts the outlet of said conduit 13. The large and the small spray nozzles 3 and 2 work in a normal manner, the fuel is mixed with air before reaching the suction pipe 4, the air flowing through the adjusted intake 8.

When the flying machine flies in inverted load conditions, the working of the carburetor is modified as follows. The slide 17 is displaced on its guide and closes the opening of the conduits 13 and the fuel from the chamber 15 is conveyed through the conduit 14 to the chamber 1, the level in this chamber being kept constant also in this case by the float 9, the needle 12 whereof works by its opposite end. The spray nozzle —a— then comes into action and receives braking air through the conduit —b—, while it conveys the air and fuel mixture into the Venturi tube 5a. The spray nozzles 2 and 3 are then out of work.

Referring to Figure 2, it is apparent that the pivot 10a of the lever 11a fast with the float 9 is situated about in the middle position of this lever and this latter carries at one end a head 11b fitted in a hollow 12b of the needle 12a. This needle is guided in its displacement by suitable projections 1b formed in the space 1a and works alternatively for controlling the outlet of the conduits 12 and 13, respectively, extending from the chamber 15. Owing to the inverted action of the constant level device mounted in the chamber 1 the slide 17 working by gravity is replaced by a float 20 provided with conical ends 21 and 22 in order to close the opening of the conduits 13 and 14, respectively.

In case the flying machine flies in its normal position, on filling the chamber 15 the float 20 remains practically always lifted, thus closing the opening of the conduit 13 and the fuel flowing through the opening 16 is conveyed to the chamber 1 through the conduit 14, the outlet whereof is controlled by the needle 12. It is apparent that during inverted flight by the displacement of the float 20 in an opposite direction the carburetor works further in the same manner as described above.

Referring to Figure 3 showing a modification of the construction shown in Fig. 2, the float 20 is replaced by a slide 17a with conical ends and in this case the arrangement of the channels 13a and 14a extending from the chamber 15 to the chamber 1 is inverted, while the working of the carburetor remains unvaried.

What I claim is:

1. A carburetor for aircraft engines comprising in combination with a constant level chamber, a distributing chamber connected with said constant level chamber through two separate conduits, a float in said constant level chamber and means carried by said float for closing alternatively one end of said conduits and a slide in said distributing chamber for closing alternatively the other ends of said conduits. 70 75

2. Carburetor for aircraft engines comprising in combination with a constant level chamber, a cover for closing said constant level chamber, a distributing chamber communicating with the fuel inlet, a conduit formed in the bottom of the constant level chamber connecting said distributing chamber with the constant level chamber, a conduit formed in the cover connecting said distributing chamber with the upper portion of the constant level chamber, the inlet and outlet openings, respectively, of said conduits being in alignment, a slide in the distributing chamber having conical ends co-operating alternatively with the inlet openings of said conduits, a needle having conical ends carried by the float and co-operating alternatively with the outlet openings of said conduits. 80 85 90 95

3. Carburetor for aircraft engines comprising in combination with a constant level chamber and a float in said chamber a distributing chamber connected with said constant level chamber through an upper and a lower conduit, means in said distributing chamber for controlling by gravity the inlet openings of said conduits, means in the constant level chamber acted upon by the float for controlling the outlet openings of said conduits. 100 105

In testimony that I claim the foregoing as my invention, I have signed my name.

TRANQUILLO ZERBI.
